UNITED STATES PATENT OFFICE.

GEORGE M. HINKLEY, OF MILWAUKEE, WISCONSIN.

SAW-MILL SET-WORKS.

SPECIFICATION forming part of Letters Patent No. 291,544, dated January 1, 1884.

Application filed October 12, 1883. (No model.)

To all whom it may concern:

Be it known that I, GEORGE M. HINKLEY, of Milwaukee, in the county of Milwaukee and State of Wisconsin, have invented certain improvements in Saw-Mill Carriages, &c., of which the following is a specification.

My invention relates to saw-mill carriages; and it consists in novel devices for adjusting and setting the knees, in forming the head-blocks with beveled ends or guards to prevent injury from contact with the bar of the log-turner or other body, and in other features and details hereinafter more fully explained.

In the accompanying drawings, Figure 1 represents a perspective view of a saw-mill carriage complete; Fig. 2, a vertical transverse section through the same from front to rear; Fig. 3, a transverse section of the sliding knee and the arc formed upon or secured thereto to receive the locking-bolt of the knee-setting lever; Fig. 4 a plan, Fig. 5 a side elevation, and Fig. 6 a front elevation, of the nose of the head-block; Figs. 7 and 8, respectively, a plan and front elevation, showing a slight modification of the same.

The first part of my invention relates to means for adjusting the knees upon the carriage to the same line, as will be readily understood from the following explanation, taken in connection with Fig. 2.

A represents the saw-mill carriage, mounted upon wheels B, and provided with a longitudinal shaft, C, upon which are secured, at proper intervals, pinions D, which serve to move the knees E forward and backward upon the carriage, as usual, the knees being formed with lateral ribs or flanges a, which travel in grooves b in the head-block. In order that one knee may be advanced more than another, when required to accommodate tapering logs and bring the front side thereof parallel with the saw, a rack, F, is provided to mesh with the pinion D, said rack being made separate from but arranged in grooves in the under side of knee E, as shown in Figs. 1, 2, and 3, the knee being connected with said rack by means of a link, c, jointed at one end to lugs or ears d, formed upon said rack, and at the other end to a hand-lever, G, pivoted in the knee at e. By reason of this connection it will

be seen that the knee may be moved back and forth in the head-block by moving the hand-lever G, the rack remaining relatively fixed because in mesh with pinion D of the shaft C. This forms a very simple and cheap connection, which works well in practice, though I desire to say here that beyond the specific construction and arrangement of parts this manner of adjusting one knee independently of the others is not claimed by me, being old 55 and well known.

The lever G carries a locking bolt or pin, f, to engage in a rack, and thereby to hold the lever at any required adjustment, the bolt being pressed downward by a spring, g, and connected by a wire or rod, r, with a hand-piece, s, by which it may be withdrawn. In the practical use of such machinery, difficulty is experienced in bringing the several knees exactly into line on the carriage and parallel with the 60 face of the saw, owing to a slight difference in the setting of the pinions on shaft D, in the mounting of the head-blocks upon the carriage, or from other causes, which render it almost impossible to secure such alignment under 65 ordinary construction. To overcome this difficulty, I form the recesses or cavities for the entrance of locking-bolt f in an adjustable strap, so that the bolt may be permitted to enter a recess in the strap and carry said strap 70 forward or backward with the lever, as the case may be, until the lever moves the knee to the exact position required, when the strap is firmly secured in such position. Referring again to Figs. 2 and 3, this adjustment will be 75 more fully explained.

The lever G is pivoted to the sliding knee at e, as above mentioned, and swings in a vertical plane close to the upright face of a semi-circular casting, H, the outer face of which is 80 an arc of a circle concentric with the pivot e of lever G. This may be cast with or bolted to the knee E, and is formed at or near each end with a perforated lug or ear, g.

I represents a metallic strap, perforated or 85 recessed at regular and suitable intervals to receive the locking-bolt f, the ends of which strap are rounded, threaded, and passed through the ears g, and furnished with nuts h, as shown, the body of the strap being bent 90

around the outer face of the arc, as in Fig. 2. Before turning up the nuts to secure the strap in place, one knee of the series is brought to place, and the others are then adjusted, 5 one or more of the knees being provided with the adjusting-lever G and attendant parts, as circumstances may require. After the first knee is brought to position, the second is carefully adjusted forward or back by a movement of the lever G until its front face is exactly in line with that of the first knee, the strap I moving with the lever because of the engagement of the locking-bolt f therein. It 10 is of course to be understood that this adjustment is comparatively slight, as the knees are set approximately close in line in first mounting the parts. When the second knee is brought exactly into line with the first, the nuts h, at both ends of strap I, are screwed 15 up tight, and the strap is thereby secured firmly and accurately in place. In this way absolute accuracy may be readily secured.

It is obvious that wedges may be passed 20 through slots in the end of the strap, instead 25 of employing nuts, that the same result may be secured by providing the rack with adjustable lugs for the engagement of bolt f, by employing an extensible link in place of the simple link c, or by making the fulcrum of 30 lever G and the rack adjustable, and therefore, while I deem the construction described and shown as the best for the purpose, I do not limit myself to the precise details shown, but consider such modifications as within my invention. 35

The next feature of my invention consists in beveling the forward ends of the head-blocks, or providing them with inclined guards to ward off or move aside the bar of the log-turner or any other object they might come 40 into contact with when the carriage is in motion. This will be better understood upon referring to Figs. 4 to 8, inclusive.

Heretofore the head-blocks have universally 45 been made with square noses or forward ends, which, coming in contact with the bar of the log-turner or other obstruction, were often broken thereby, owing to their inability to deflect or move back such obstruction. Under 50 my construction, however, the vertical sides of the nose or forward end of the head-block are beveled, as shown in plan in Fig. 4, and in front or end elevation in Fig. 5, thereby forming inclines i, which serve to ward off 55 and crowd back any obstruction capable of moving back, but which could not be moved in the direction of travel of the carriage. These inclines will ordinarily be formed in casting the head-block; but in the case of machinery already in use they may be formed 60 separately, and bolted or otherwise secured in place, as shown in plan in Fig. 7, in front elevation in Fig. 8, and in perspective in Fig. 1.

65 I do not in this application claim the truck-boxes and the lubricating device, as these

features are made the subject-matter of a separate application, as a division of this case, in compliance with an official requirement to that effect.

Having thus described my invention, what I claim is—

1. The combination, in a saw-mill carriage, of a head-block, a knee sliding therein, a rack-bar sliding in said knee, a pinion secured upon the feed-shaft and meshing with the rack, a lever fulcrumed in the sliding knee, and a link connecting the lever and the rack, substantially as shown. 70

2. In combination with a saw-mill head-block and a knee arranged to slide therein, a rack meshing with a feed-pinion and separate from the knee, a lever to move said knee independently of the rack, provided with a locking device, and a rack to receive said locking device, said rack being adjustable, substantially as described, to permit it to be brought into proper relation to the locking device. 80

3. In combination with a saw-mill head-block, a knee movable thereon, a lever connected with said knee and adapted to move the same, a locking-bolt to hold said lever at any desired adjustment, and a rack to receive the locking-bolt, said rack being adjustable, 90 substantially in the manner and for the purpose explained. 95

4. In combination with a sliding knee, E, provided with arc H, adjusting-lever G, provided with a locking-bolt, F, and a recessed strap, I, applied to and adjustable upon the arc, substantially as and for the purpose explained. 100

5. The combination, substantially as shown and described, of a head-block, a knee, E, 105 movable thereon, a rack, F, movable independently of the knee, a hand-lever, G, pivoted to the knee and provided with a locking-bolt, f, a link, c, connecting the hand-lever and the rack F, an arc, H, upon the knee 110 provided with ears g, and a strap, I, adapted to receive the locking-bolt f, having its ends passed through the ears g, and provided with nuts h. 115

6. The herein-described method of aligning knees upon a saw-mill carriage and adjusting their locking devices to maintain such alignment, which consists in bringing one knee to a given line, then adjusting each succeeding knee to the same line, moving the rack with which its locking-bolt engages to proper position to receive said locking-bolt while the knee is in such adjusted position, and making the rack fast at such point. 120

7. In combination with a saw-mill carriage, 125 a head-block mounted thereon and having the side faces of its forward end or nose beveled from the sides inward toward the center, the narrowest portion being at the extreme front end, substantially as and for the purpose explained. 130

8. In combination with a traveling saw-mill

carriage, a head-block having its nose or forward end narrowed and provided with inclined faces connecting the narrow ends and the sides, as and for the purpose explained.

5 9. A saw-mill head-block narrower at its extreme forward end than in rear thereof, and having its narrow end and its sides connected

by inclined faces, as shown, whereby it is adapted to deflect obstructions.

GEORGE M. HINKLEY.
